BOILER

Henry G. Schaefer, Yonkers, N. Y.

Application November 19, 1941, Serial No. 419,759

7 Claims. (Cl. 122—234)

This invention relates to boiler constructions for producing steam or hot water.

It is the primary aim and object of the present invention to provide a boiler construction which has a higher steam or hot water production per unit area of heating surface than the conventional boiler constructions.

It is another object of the present invention to provide a boiler construction which produces steam or hot water after an exceptionally short time from a cold start.

It is also among the objects of the present invention to provide a boiler construction which takes up little room and is equally adaptable for industrial and domestic purposes of all kinds, and which may be built strong and durable from relatively simple parts and at a low cost.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

Fig. 1 is a vertical section through a steam generator embodying the present invention.

Fig. 2 is a horizontal section taken substantially on the line 2—2 of Fig. 1.

Fig. 3 is an enlarged fragmentary section through the wall of the boiler in the present steam generator.

Figs. 4 and 4a are sections similar to Fig. 3 and show modified wall constructions of the boiler.

Fig. 5 is a vertical section through a hot water heater which also embodies the present invention.

Referring to the drawings and particularly to Fig. 1 thereof, the reference numeral 10 designates a steam generator which comprises a furnace 12 and a boiler 14 of any suitable metal. The boiler 14 is spherical in shape and preferably consists of two halves 16 and 18 whose abutting surfaces 20 and 22, respectively, are preferably ground and firmly secured to each other by means of a split ring 24. The split ring 24 is closed by bolts 26 and has an internal groove 27 whose oppositely bevelled side walls 28 are clamped over similarly bevelled surfaces 30 of the spherical

halves 16 and 18, respectively. The spherical boiler 14 is provided with a cylindrical downward extension 32 whose lower end is connected with a T-piece 34 which provides communication between said boiler extension 32 and a water feed line 36 as well as a waste line 38, respectively. Communicating with the steam chamber 40 in the boiler 14 above the water level 41 therein is a steam conduit 42 through which the steam passes to its place of application.

Substantially surrounding the boiler 14 is the furnace 12 which comprises a heat conductor in form of a shell 44 of any suitable refractory material which provides a spiral passage 46 about the boiler 14. The upper end of the spiral passage 46 communicates with any suitable flue passage 48. Projecting at 50 through the refractory shell 44 and into the lowermost portion of the spiral passage 46 therein is the nozzle end 52 of any conventional combustion burner 54 which is housed in a lateral extension 56 of an outer casing 58 (see also Fig. 2) and may use oil for fuel. The outer casing 58, which is preferably of sheet metal, surrounds the shell 44 and is open at the top as at 60 for admission of atmospheric air to the burner 54 for combustion purposes. The air in the outer casing 58 is not only preheated for combustion purposes by the shell 44, but also effectively heat-insulates said outer casing from said shell. The nozzle end 52 of the burner 54 is furthermore so disposed (Fig. 2) that the flame 62 is directed substantially tangentially of the spiral passage 46 so as to cause the products of combustion to progress through said spiral passage with the least obstruction and to come into effective heat-exchange relation with the more remote portions of the boiler 14 before said products give up most of their heat.

Rotatably mounted in the boiler in suitable bearings 70 and 72 is a shaft 74 which carries an agitator 76. The agitator 76 comprises preferably diametrically opposite, arc-shaped blades 78 which are comparatively narrow radially of the spherical boiler 14 and extend in close proximity to the inner boiler surface 80 substantially from the bottom thereof to a point considerably above the water level 41 for reasons which will appear obvious later. The agitator 76 may further comprise diametrically opposite blades 84 which extend into close proximity to the inner surface 86 of the cylindrical downward extension 32 of the boiler. The blades 78 and 84 of the agitator are preferably integral with suitable spiders 88 and hubs 90 of which the latter are fast on the shaft 74. The upper end of the agitator shaft

14 may extend through and beyond the vertical branch 42a of the steam conduit 42 and carry on its projecting end a pulley 92, driven from the motor shaft (not shown) of the burner 54 through a suitable belt connection (not shown). Mounted on the inner wall of the spherical boiler 14 by means of suitable brackets 96, for instance, is a substantially horizontal partition 98 which has a central opening 100. Mounted on the partition 98 by angles 102, for instance, and projecting into the opening 100 are stationary blades 103 of a steam turbine 104 whose rotary blades 106 are mounted on the agitator shaft 74 immediately above said stationary blades. When steam is consumed, steam under pressure from the boiler 14 passes through the turbine 104 which creates a torque on the agitator shaft 74 that may or may not be sufficiently large to propel the agitator 76 at a desired speed. If the torque from the turbine 104 is sufficiently large to accomplish this, the previously described mechanical drive for the agitator shaft 74 may be dispensed with. On the other hand, the steam turbine 104 may be dispensed with and the referred mechanical drive for the agitator solely resorted to, if the drop in steam pressure occasioned by operating the turbine is undesirable. Should any condensation of steam take place in the turbine 104, the latter also effectively separates the condensed water particles from the steam and assists in the immediate re-vaporization of the former. This is accomplished by the rotary turbine blades 106 from which the water particles are thrown with a centrifugal force against the boiler wall where they are either re-vaporized or returned to the boiler water, depending on the heat conditions.

The agitator 76 is rotated preferably at such speed that the water in the boiler spins rapidly so that its normal level 41 assumes the concave shape indicated in dot-and-dash lines at 41a in Fig. 1. In this way, considerably more of the heat transfer area of the boiler 14 is contacted by the water than if the latter were not agitated, and the steam production is accordingly increased. The agitation of the water, which results in the concavity of its level, secures several other advantages which will be described hereinafter. It is to deepen as much as possible the water trough formed by the concave deformation 41a of the water level that the agitator blades 78 extend considerably above the normal water level 41.

The agitator 76 imparts to the water nearest the inner boiler surface 80, 86 a considerable centrifugal force so that said water will continuously wipe steam bubbles off the boiler wall as soon as developed and replace them with water to be transformed into steam. Hence, the steam bubbles are not permitted to cling to the boiler wall until eventually breaking away therefrom as in the case of a boiler wherein the water is static, but they are continuously shaken off by the centrifugal force of the water while they are still of a small size. Moreover, the water swirling against the boiler wall will be under pressure which is created by the centrifugal force, and this pressure actually squeezes the liberated steam bubbles into the steam chamber 40 since it is the path of least resistance for them to follow. Thus, by agitating the water as described, the steam production of the boiler per time unit is greatly increased over that of a boiler in which the water is static.

To increase the heat-exchange area between

the water and the boiler, the inner surface 80 of the latter, and, if desired, also the inner surface 85 of the downward extension 32, thereof, may be provided with a multitude of deformations 110 which are shown, by way of example, as narrowly spaced grooves of V-shaped cross-section. These grooves 110 (see also Fig. 3) may be provided by any suitable method such as rolling or cutting. In order that the grooves 110 may not interfere with the spinning motion of the water in the boiler about a vertical axis, they lie in parallel horizontal planes. Even greater efficiency may be gained, however, by forming the grooves 110 in the fashion of a screw thread (Fig. 4a) with a single or multiple thread, in which case the whirling water at the boiler wall is given a slight upward surge. The natural buoyancy of the steam bubbles then cooperates with the whirling and slightly upwardly surging water in readily removing the steam bubbles from the boiler wall where they were generated. Since the tensile strength of the boiler wall is determined by the wall thickness from the bottom of the grooves 110 in one surface of the wall to the other surface thereof, these grooves 110 are preferably made very shallow (Fig. 3) so that very little additional thickness is required of the boiler wall over that of a wall having no grooves in it and being of the same tensile strength. To accomplish a substantial increase of the heat-exchange area between the water and the boiler, the grooves 110 need not be deep at all but may be rather shallow, in which case a greater number of the shallow grooves is provided. The heat exchange area between the products of combustion in the spiral passage 46 and the boiler 14 may also be augmented by suitably providing on the outer surface of the latter a multitude of heat-conductive fins 112 (Fig. 4). Soda ash, sodium phosphate or their equivalent are usually added to the boiler water to inhibit scale formation on the boiler wall. This in addition to the brushing action of the agitated boiler water prevents even the formation of traces of scale in the grooved boiler wall over a long period of use.

The boiler 14 has been made spherical in shape so as to require for a given internal steam pressure a wall thickness which is smaller than the wall thickness required of a boiler of any other shape for the same steam pressure.

In conclusion, the present steam generator secures, among other advantages, the following, more prominent advantages. The spherical shape of the boiler permits a minimum wall thickness for a given steam pressure, resulting in a considerable saving in material and a light weight of the boiler, as well as a quick transfer of heat from the heating medium to the water in the boiler. The latter advantage contributes to the quick production of steam from a cold start of the boiler. The agitation of the boiler water causes immediate replacement of the developed steam bubbles on the boiler wall with water particles and a squeezing of the liberated steam bubbles into the steam space above the water level, as well as a considerably increased contact area between the boiler water and the heated boiler wall, resulting in a very high steam production per time unit and per unit area of the boiler. Furthermore, the agitated water, besides effectively preventing the formation of even traces of scale on the boiler wall, will not permit undue "priming," i. e., the well-known injection of water particles into the steam bubbles when the latter break through the seething surface

of static boiler water. Due to the spherical shape of the boiler and the agitation of the water therein, the contact area between the water and the boiler wall is very large despite a very small water supply in the boiler. This factor contributes largely to a quick steam production from a cold start of the boiler. Also, since the water supply in the boiler is so small, the steam space above the water level is correspondingly large and readily permits the equalization of internal steam pressure fluctuations so that the steam supply in said chamber may have a most uniform out-flow. The large steam chamber, which is in part defined by the concave or distorted parabolic water level 41a, affords also an ideal "steam-disengaging" space where the steam may gather and rid itself safely of water particles left on the surface of the steam bubbles. The grooving of the inner boiler surface greatly increases the contact area between the boiler and the water therein, resulting in a further, large increase in the steam production per unit area of the boiler. The relative thinness of the boiler wall occasioned by its spherical shape, in conjunction with the grooving of the inner boiler surface and the agitation of the boiler water, permits the transfer of a large amount of heat through the heating surfaces of the boiler per hour and results in an accordingly large capacity of the boiler.

Fig. 5 discloses a hot water heater whose boiler construction embodies the present invention. Thus, the boiler 114 is spherical and has in its inner surface deformations 116 which are similar to the grooves 116 in Figs. 1 and 3. The boiler 114 has at its bottom a water inlet conduit 117. There is also provided in the boiler 114 an agitator 118 which may be the same as the agitator shown in Fig. 1. The agitator shaft 120 may be driven from any suitable prime mover through a non-disclosed belt connection including a pulley 123 on that end of the agitator shaft which extends beyond the hot water outlet pipe 124. A turbine 126, similar in construction to the turbine 104 in Fig. 1, may also be provided in addition to, or in the possible absence of, the mechanical agitator drive which includes the pulley 123. The stationary blades 128 of the turbine may be mounted by bracket 130, for instance, on a horizontal partition 132 whose periphery abuts the boiler wall. The partition 132 may be secured in place by bolts 133 and nuts 134 of which the former may be conveniently welded to the boiler wall as at 135. The rotary blades 136 of the turbine are mounted on the agitator shaft 120. The grooves 116 in the inner surface of the boiler greatly increase the contact area between the hot boiler wall and the water, resulting in a greatly increased production of hot water per unit area of the boiler. The agitation of the water in the boiler results in a considerable pressure of the water against the boiler wall, resulting in a most intimate contact between them and an accordingly thorough heat exchange.

I claim:

1. The combination of a boiler having an outlet on top and an inner surface of revolution about a substantially vertical axis, a rotary shaft 5 in the boiler extending coaxially of said vertical axis, an agitator mounted on said shaft, a substantially horizontal partition in the boiler near said outlet and having a central opening, and a turbine having cooperating stationary and rotary blades, the stationary blades projecting into said opening and the rotary blades being carried by said shaft above said opening.
2. The combination of a vessel containing water and having an inner surface of revolution, 15 means providing a passage for a heating medium in heat-exchange relation with the outer surface of said vessel, and an agitator in the vessel rotatable about the axis of said surface of revolution, the latter surface being provided with a multitude of shallow grooves extending circularly 20 about the axis of rotation of said agitator.
3. The combination of a spherical vessel containing water and having a multitude of shallow circular grooves in its internal surface extending in substantially horizontal planes, respectively, 25 means providing a passage for a heating medium in heat-exchange relation with the outer surface of said vessel, and an agitator in the vessel rotatable about a substantially vertical axis of the sphere and extending in close proximity to said internal surface.
4. In a steam generator, the combination of a spherical boiler having in its internal surface a thread of many turns about a vertical axis, 30 means providing a passage having a heating medium in heat-exchange relation with the outer surface of said boiler, and an agitator in the boiler rotatable about a substantially vertical axis of the sphere and extending in close proximity to said internal surface.
5. The combination of a boiler having an outlet on top, a substantially vertical shaft in said boiler, an agitator in the boiler mounted on said shaft, a substantially horizontal partition in the 35 boiler located near said outlet and having an opening, and a turbine having cooperating stationary and rotary blades, the stationary blades projecting into said opening and the rotary blades being carried by said shaft above said opening.
6. The combination of a vessel containing water and having a multitude of depressions in its internal wall to increase the heat-exchange area between the vessel and the water therein, means 45 for heating said vessel, and a rotatable agitator in said vessel extending into close proximity to the inner surface of the latter.
7. The combination of a vessel containing water, means for heating the wall of said vessel and a rotatable agitator in said vessel, the inner surface of said wall being provided with a multitude of substantially parallel, shallow grooves extending transversely to the axis of rotation of said agitator.
